UNITED STATES PATENT OFFICE.

SAMUEL SHAW, OF NEWTON, MASSACHUSETTS, ASSIGNOR TO THE MURDOCK PARLOR GRATE COMPANY, OF MASSACHUSETTS.

VENTILATING-GRADE.

SPECIFICATION forming part of Letters Patent No. 471,575, dated March 29, 1892.

Application filed May 20, 1889. Serial No. 311,444. (No model.)

To all whom it may concern:

Be it known that I, SAMUEL SHAW, of Newton, in the county of Middlesex and State of Massachusetts, have invented a certain 5 new and useful Improvement in Ventilating-Grates, of which the following is a specification.

My invention relates to open grates; and it consists in certain new and useful constructions and combinations of the several parts thereof, substantially as hereinafter described and claimed.

In the drawings, Figure 1 is a front view of an open grate provided with my improvements. Fig. 2 is a top plan view of the same. Fig. 3 is a vertical section on line $\alpha\alpha$ of Fig. 2. Fig. 4 is a vertical section on line $z\alpha$ of Fig. 2. Fig. 5 is a horizontal section on line yy of Fig. 4. Figs. 6 and 7 are enlarged 20 detail views of parts of the grate, showing the method of operating the dampers.

1 is the grate, which is inclosed in a casing 12, supported upon the base part 3. The casing 12 is open above the grate on its front 25 side in the ordinary manner and has a smoke-flue 4 leading from its upper part to the chimney for the escape of smoke and gases from the fuel consumed in the grate and to create a draft for burning the latter. The 30 casing 12 is cut through at its back part and ends opposite to and for some distance above the grate, and a lining 10 is bolted to the casing all around the grate part which holds the fuel, and this lining has corrugated portions 35 55, which project through the cut-out portions of casing 12 and are fluted longitudinally, so as to afford more radiating-surface for the air to come in contact with on their rearward faces. By this construction I am enabled to 40 have the advantages of a cast-iron lining to the grate, which conveys heat more rapidly and readily than fire-brick, because the lining 10 is made of cast-iron, while the casing 12, into which it is fitted, is made of wrought-iron 45 sheets and form tight joints with the cast-iron, which do not warp or draw open like those made between two cast-iron pieces and thus allow gas to escape into the air-space between casings 12 and 13 behind the grate. 50 The base 3 is in the form of an inclosed box meeting the lower edges of the casing 12

around the grate and sustaining the grate in front, and it has draft holes or places 6 6 cut through its exposed front part, which are closed by the damper 7, Fig. 4, operated by the knob 55 8, by which it is slid longitudinally to open or close the air-draft in the usual manner. A front plate 9 forms a frame or face around the open part of the fire-place, being joined to the casing 12 around its inner edges and 60 resting against the brick-work of the fire-place at its outer edge on the back side.

Around the casing 12 at some distance from it is a casing 13, which completely incloses casing 12, so as to leave a space between them 65 around the ends, back, and top of the grate. The casing 13 has its front edges resting against the frame-plate 9, to which it is attached air-tight. A casing 14 incloses the casing 13 in a similar manner outside of that, having its front edges secured to the frame-plate 9, so as to leave a space all around between the two at the ends, top, and back of the grate. I have thus provided two complete air-spaces between the casings 12 13 and 13 14 to intercept the radiation of heat from the grate at its ends, back, and top. The air-space between casings 13 and 14 is what is known as a "dead-air" space, being merely for the purpose of preventing the loss of heat by radiation from 70 the inner air-space. The smoke-flue 4 passes through both of these air-spaces and through the casings 12 13 14 out into the chimney. The inner air-space between casings 12 and 13 has an induct-flue 15 leading into it at the 75 bottom, as shown in Figs. 3 and 4, which may be connected with a pipe leading out of doors or open into the room in which the grate stands by having the grate supported on feet or raised parts under the corners of the base. 80 Just above the opening 15 is the damper 16, turning upon pivot 17, which closes the outlet of the flue 15 and shuts the air off from passing up between casings 12 and 13 whenever desired. Just above this damper 90 95 are horizontal shelves 18 18, projecting laterally inward from the casing 13, so as to partially fill the space between that and casing 12 and only leave it open immediately around the latter opposite the edge of each shelf. The 100 space between the edge of each shelf and the inner casing will be particularly observed to

be of substantially even breadth all around the lining, so as to form a true flue-throat for the upward flow of the heated air, thereby avoiding obstructing eddies, which would 5 check or even destroy it in this case where it is delivered out of the grate at so short a distance above its point of entry thereunder and can have no long chimney attached to overcome these eddies by its suction or draft. It is 10 a well-known fact that this even throat—*i. e.*, not wider at one point than another—in an air-passage is essential to a perfect and even upward flow of heated air, which rises by its own buoyancy. It will also be observed that 15 the throat formed by each shelf 18 above the lowermost one is a little wider than the one below it. This allows for the expansion of the air as it heats in its upward flow and accelerates the latter. These shelves 18 corre- 20 spond in their location with the longitudinal flutings in the lining 10, so as to force the air in and out around those flutings and against the casing 12 and compel it to become heated by contact therewith. These shelves 18 also 25 perform another function in holding between them a certain part of the air and preventing its escape upward, because that which rises from the inlet 15 is carried by the suction or draft past what is retained between the shelves 30 18, and the latter serve to prevent the heat from radiating through casing 13, because it cannot readily pass through the bodies of air retained between the shelves 18. This pecu- 35 liar function of the shelves in interposing bodies of air confined by them between the ascending current and the casing 13 (opposite to the burning fuel) is due to the fact that the air can only escape past the inner edge of each shelf 18, the ends and rear edge of the 40 shelf being tightly fitted all around in the casing 13. If the shelves did not fit casing 13 at its ends, the air would escape from between the shelves constantly past those ends and not be forced past the inner edges of shelves 45 18 and bodies of air would not be confined between the shelves 18 and thus interposed between the ascending column of air and the casing 13 opposite to the burning fuel in the grate. This utilization of shelves 18 to con- 50 fine bodies of air between them and so arrest radiation rearward from the grate, as well as to force the air past the inner edges of the shelves next to the corrugated lining 10, is, I believe, new, because heretofore when shelves 55 have been used they have not been made to fit tightly in the outer casing, corresponding to 18, so as to compel all the air to pass their inner edges next to the backing of the grate through a throat of substantially even breadth 60 in all its parts.

At the upper end of the space between casings 12 and 13 are located three dampers 19 20 21, turning on horizontal pivots *a a* at their centers, so as to close the upper end of the 65 space when desired. These dampers are operated by means of the knob 22, (shown in Figs. 1 and 2,) which slides up and down

through slot 23 in the frame-plate 9. When these dampers are thus opened, the air will escape through the perforated plate 27, which 70 forms a part of the frame-plate 9 and covers the space above the grate between casings 12 and 13, as shown in Figs. 3 and 4. Thus the heat radiated backward from the grate is made to heat an additional air-supply for the 75 room and is not lost, as it otherwise would be. On each side of the smoke-flue 4 a hot-air pipe 28 leads upward from the space between casings 13 and 14, and a short distance above the casings these hot-air pipes are connected 80 by the horizontal drum 29, which has a central flue 30 leading upward. The flue 30 may be continued up the chimney to an upper room, where it discharges hot air into it when desired. Both hot-air pipes 28 have a damper 85 31, Figs. 3 and 4, placed in the space between casings 13 and 14 of the ordinary fly pattern, pivoted horizontally in the usual manner, and having a short arm 32 projecting outward from its face. To the outer end of this arm is pivoted the sliding rod 33, which projects outward through the frame-plate 9 and has on its outer end the knob 36. By pushing in and out on this knob the damper 31 will be closed or opened at pleasure. It is to be opened 90 when the dampers 19 20 21 are closed, and vice versa. The heated air enters the space between casings 13 and 14 through the opening 34 in the casing 13 between the dampers 19 20 21 and the damper 31. 95 100

The damper 16 is operated by means of a lever 37, attached to the revolving shaft 38. The inner end of its shaft and its connection with the damper is shown in Figs. 8 and 9. The shaft has its inner end journaled in the 105 post 39 and carries at right angles to it the finger 40, which impinges against the lower face of the damper 16. When the lever 37 is thrown over, turning the rod 38, it carries the finger 40 with it and turns the damper 16 upward on its pivot, opening the flue and allowing the air to pass up between casings 12 and 13, as before described. By reversing the movement of the lever 37 the finger 40 is withdrawn from beneath the damper 16 and the 110 latter closes by its own weight. 115

The smoke-flue 4 is provided with dampers 41 42, turning on horizontal pivots. To each damper is pivoted the double link 43, which is in turn pivoted at 44 to the revolving plate 120 45. The latter turns on its pivot 46 in the flue and has a depending arm 47 projecting downward out of the flue in reach of a poker. By drawing this arm forward from the position shown in Fig. 4 the double link 43 will close 125 the dampers 41 42, while by pushing it back again they will be opened, as shown.

What I claim as new and of my invention is—

1. The combination of the open grate 1, the 130 casing 12, surrounding the same and provided with a horizontally corrugated or fluted wall 5, forming the grate-lining, the outer casing 13, surrounding casing 12, so as to leave a ver-

tical space between them, and a series of horizontal shelves 18, fitting against said casing 13 and presenting their exposed edges opposite the flutings of casing 12, so as each to form an air throat or passage within the casings of substantially even breadth in all its parts, whereby the sheet of air is forced to follow the flutings directly upward and is not broken into disturbing eddies which interrupt the same, substantially as described.

2. The combination of the open grate 1, the casing 12, surrounding the back and ends of the same and provided with horizontally-fluted back and end walls 5, forming the grate-lining, the outer casing 13, surrounding casing 12 at the back and ends of the grate, so as to leave a vertical space between them, and a series of horizontal shelves 18, fitting against said casing 13 and presenting their exposed edges opposite the back and end flutings of casing 12, so as each to form an air throat or passage within the casings of substantially even breadth in all its parts, whereby the sheet of air is forced to follow the flutings directly upward and is not broken into disturbing eddies which interrupt the same, substantially as described.

3. The combination of the open grate 1, the frame-plate 9, surrounding the front of the same, the casing 12, surrounding the back and ends of the same and extending forward over it and joined to the frame-plate, the casing 13, surrounding the casing 12, so as to form a space between them around and above the grate, and having its upper edge terminating short of the frame-plate, so as to leave a passage between them, the air-inlet 15, the outer casing 14, surrounding the casing 13, so as to form an air-space between them, and joined to the frame-plate around and above the latter, the pipe 28, leading out of the space between casings 13 and 14, and the damper 31 between them, whereby when said damper is opened said last-named space conveys the air to the pipe 28, and when it is closed the same becomes a dead-air space, substantially as described.

4. The combination of the open grate 1, the wrought-iron casing 12, inclosing the back and ends of the same, the cast-iron grate-lining 10, attached to the said casing around the back and ends of the grate and having horizontal fluted portions 5 projecting through spaces formed in said casing, the casing 13, surrounding casing 12 so as to leave a space between them, the air-inlet 15, opening into the bottom of said space below the grate, and an air-outlet opening out from said space above the grate, whereby the angular joints

separating the said space between casings 12 and 13 from the grate and fuel are formed of wrought metal and air-tight, and the corrugated grate-back of cast-iron, against which the fuel rests, has the air passing upward between casings 12 and 13 impinging against it, and is joined to the wrought-iron casing 12 on their flat faces, substantially as described.

5. The combination of the open grate provided with the frame-plate 9, the rod 38, projecting through the front of said frame and journaled in post 39, the lever 37, attached to the outer end thereof, and the arm 40, attached to the inner end thereof and projecting under the gravity-closing damper 16 in position to lift and open the same, with the latter pivoted at one edge and inclining upward and closing by the action of gravity when the arm 40 is withdrawn against the vertical face of the base-plate, whereby soot, ashes, &c., falling upon the upper side of said damper are prevented from lodging between its free edge and the casing, against which it closes, and obstructing its being opened or closed, substantially as described.

6. The combination of the open grate 1, the casing 12, surrounding the same and provided with a horizontally corrugated or fluted wall 5, forming the grate-lining, the outer casing 13, surrounding casing 12 so as to leave a vertical space between them, and a horizontal shelf 18, fitting against casing 13 closely at its back and ends and presenting its exposed edge opposite a fluting of casing 12, so as to form a throat or passage within the casings of substantially even breadth in all its parts, whereby the sheet of air is forced to follow the fluting directly upward and is not broken into disturbing eddies which interrupt the same, substantially as described.

7. The combination of the open grate 1, the casing 12, surrounding the same and provided with a horizontally fluted or corrugated wall 5, forming the grate-lining, the outer casing 13, surrounding casing 12 so as to leave an air-space between them, and a series of horizontal shelves 18, fitting against said casing 13 and having each succeeding one presenting its exposed edge toward the lining 12, so as to form a wider throat or passage between them than the shelf below it, whereby additional escape is given to the ascending air as it heats and expands in rising past the shelves, substantially as described.

SAMUEL SHAW.
